(57) CLAIM

The ornamental design for an abrasive sharpener with a fire starter, as shown and described.

DESCRIPTION

FIG. 1 is a front perspective view of the ornamental design for an abrasive sharpener with a fire starter of the invention;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof;

FIG. 7 is an opposite side elevational view thereof; and,

FIG. 8 is a bottom perspective view thereof.

The broken lines in the figures illustrate portions of the abrasive sharpener of the invention that form no part of the claim.
